DISTILLATION OF SULFURIC ACID
TREATED HYDROCARBON OILS

Harry L. Allen and Herbert G. Kleinguenther,
Philadelphia, Pa., assignors to Allied Chemical
& Dye Corporation, New York, N. Y., a corpora-
tion of New York

No Drawing. Application September 11, 1946,
Serial No. 696,346

4 Claims. (CL 196—25)

1

This invention relates to the refining of aromatic distillates, particularly those distillates obtained from coal-tar, water-gas tar and oils obtained from carburetted water-gas operations. It is particularly applicable in the refining of distillates derived from these sources which have been treated with sulfuric acid and a neutralizing agent.

In the refining of aromatic hydrocarbon oils to obtain so-called water-white distillates which are used as solvents, for example in the paint and varnish industry, or as raw materials for chemical syntheses, or as fuels for internal combustion engines, it is customary to treat the oils or fractions thereof with concentrated sulfuric acid, a neutralizing agent such as aqueous caustic soda solution and then fractionally distill the neutralized oils to recover the desired fractions of refined water-white oils. In many cases, the oils are washed with water prior to the fractional distillation step. During the distillation there is frequently encountered a copious evolution of sulfur dioxide particularly in the case of oils derived from water-gas tar and drip oil (oils collecting in manufactured gas distribution mains and holders or which are scrubbed from manufactured gas during its recovery). The sulfur dioxide thus evolved causes severe corrosion of the still, fractionating column, condenser and other parts of the distillation equipment. When steam is used in the distillation the corrosion is particularly severe owing to the formation of the highly-corrosive sulfurous acid. Furthermore, the sulfur dioxide passes into the distillate products imparting to them an objectionable acidity which must be neutralized or removed before a saleable product can be obtained.

This evolution of sulfur dioxide is due apparently to the breakdown under distillation conditions of various thermally-unstable materials such as organic sulfates and related compounds introduced during the treatment with sulfuric acid and not removed by the subsequent treatment with aqueous neutralizing agent. Various attempts have been made to combat the evolution of sulfur dioxide and the resultant deleterious effects but these attempts have generally been only partially successful or require a large quantity of reagent.

It is an object of this invention to provide an improved process for refining aromatic hydrocarbon oils.

It is a further object of this invention to provide an improved method of distilling aromatic

2

hydrocarbon oils whereby the evolution of sulfur dioxide is suppressed.

Other objects and advantages will appear hereinafter.

5 In accordance with our invention, an aromatic hydrocarbon oil which has been refined by treatment with concentrated sulfuric acid and a neutralizing agent, for example aqueous caustic soda solution, is distilled in the presence of urea or thiourea. The expression "aromatic hydrocarbon oil" is used herein to refer to those oils and fractions thereof predominately aromatic in character recovered from coal tar and water-gas tar or obtained in the coking of coal or in the manufacture of carburetted water-gas and including oils such as drip oil collecting in manufactured gas distribution and storage systems or scrubbed from manufactured gas during its recovery.

10 We have found that by distilling acid-treated and neutralized aromatic hydrocarbon oils in the presence of urea or thiourea, evolution of sulfur dioxide is substantially eliminated. As indicated above, our improved process is particularly applicable to the distillation of oils derived from 15 drip oil and from carburetted water-gas operations since such oils have a tendency to form substantial amounts of those compounds which upon subsequent distillation are responsible for the evolution of sulfur dioxide. The process is especially applicable to treatment of oil fractions 20 boiling within the range of from 70° C. to 250° C.

25 We have found that urea or thiourea even when used in small quantities is surprisingly effective in preventing the evolution of sulfur dioxide and the attendant deleterious effects upon 30 equipment and product during the distillation of acid-refined aromatic hydrocarbon oils. The invention may be carried into effect for example, by subjecting an oil, such as drip oil benzene-toluene fraction, boiling within the range of from 35 about 70° C. to about 140° C., to the action of concentrated sulfuric acid, separating the acid sludge from the oil, washing the oil with an aqueous solution of a neutralizing agent, such as 40 aqueous caustic soda, washing the neutralized oil with water and then fractionally distilling the oil in the presence of urea or thiourea to obtain a refined water-white oil requiring no further 45 treatment. The distillation may be carried out at atmospheric pressure or at subatmospheric pressure, with or without the use of live steam 50 and either batchwise or continuously.

The amount of urea or thiourea necessary to secure optimum inhibition of sulfur dioxide evolution depends on various factors including the

source of the oil and the extent of its preliminary treatment. In general, from 0.1 to 1 per cent of urea or thiourea based on the weight of the oil is sufficient to eliminate sulfur dioxide. The optimum amount of treating agent for a given charge of oil may readily be determined prior to addition of the reagent by effecting small scale distillations of small portions of the batch with different amounts of the reagents and testing the vapors for the presence of sulfur dioxide. The agent may be added directly as a solid to the oil to be distilled or it may be added as a solution in a solvent.

The following examples are illustrative of the invention:

1. An oil fraction of drip oil origin, boiling within the range from 70 to 140° C., a fraction from which benzene and toluene may be recovered by fractional distillation, previously treated with sulfuric acid and caustic soda solution, was distilled in the presence of 0.1% of urea (based on the weight of the oil). No sulfur dioxide was evolved throughout the entire course of the distillation.

For purposes of comparison another portion of the same oil fraction was distilled in the absence of any urea. By the time the temperature of the vapors being distilled had reached 133° C., evolution of substantial quantities of sulfur dioxide had begun. Sustained evolution of sulfur dioxide as in the case of continuous operation would have led to corrosion of the distillation equipment.

2. An oil fraction of drip oil origin having a boiling range of 120° to 170° C., previously treated with sulfuric acid and caustic soda solution, to which 0.1% of urea (based on the weight of the oil) had been added was distilled and tests for sulfur dioxide made during the course of the distillation. Seventy-three per cent of the oil fraction had distilled, i. e., vapors had reached 165° C. before sulfur dioxide was detected.

For purposes of comparison, a portion of the same oil fraction to which no urea had been added was distilled. Sulfur dioxide became noticeable when only six per cent of the oil fraction had distilled.

3. Another portion of the same oil fraction employed in Example 2 was distilled after the addition of 0.1% of thiourea. Forty-eight percent of the oil fraction had distilled before evolution of sulfur dioxide began.

From the foregoing it will be seen that the invention makes it possible to inhibit or eliminate the evolution of sulfur dioxide during the distillation of acid-treated aromatic hydrocarbon oils and to recover high-quality water-white distillates without further treatment.

Since certain changes may be made in the above described process without departing from the scope of the invention, it is intended that all matter contained in the above description shall be interpreted as illustrative and not in a limiting sense.

We claim:

1. In the refining of an aromatic hydrocarbon oil by treatment with sulfuric acid and subsequent distillation, the improvement which comprises eliminating excess acid from the acid-treated oil and thereafter distilling the oil in the presence of a compound selected from the group consisting of urea and thiourea.

2. In the refining of an aromatic hydrocarbon oil by treatment with sulfuric acid and subsequent distillation, the improvement which comprises washing the acid-treated oil with caustic soda solution to neutralize excess acid and distilling the washed oil in the presence of between 0.1% and 1% by weight of at least one compound selected from the group consisting of urea and thiourea.

3. The process of the preceding claim wherein the oil is separated from acid prior to washing and from caustic soda solution prior to distilling and to the separated oil between 0.1% and 1% by weight of urea is added prior to the distillation.

4. The process of the preceding claim wherein the oil is a drip oil distillate fraction of boiling range between 70° C. and 250° C.
